DESIGN FOR A GAME BOARD

Herbert L. Bradshaw, Seattle, Wash.

Application November 19, 1945, Serial No. 123,895

Term of patent 14 years

(Cl. D34—5)

To all whom it may concern:

Be it known that Herbert L. Bradshaw, a citizen of the United States, residing at Seattle, Washington, has invented a new, original, and ornamental Design for a Game Board, of which the following is a specification, reference being had to the accompanying drawing, forming a part thereof, in which the figure is a perspective view of a game board, showing my new design.

I claim:

The ornamental design for a game board, as shown.

HERBERT L. BRADSHAW.
